DESIGN FOR A COMBINED CRIB AND WARDROBE

Edmond J. Spence, Batavia, N. Y., assignor to
The Lehman Company of America, Inc., Can-nelton, Ind., a corporation of Indiana

Application June 4, 1941, Serial No. 101,290

Term of patent 14 years

To all whom it may concern:

Be it known that I, Edmond J. Spence, a citizen of the United States, residing at Batavia, in the county of Genesee and State of New York, have invented a new, original, and ornamental Design for a Combined Crib and Wardrobe, of which the following is a specification, reference being had to the accompanying drawings, forming a part thereof.

In the drawings:

Fig. 1 is a perspective view of the combined crib and wardrobe, showing my design; and

Fig. 2 is a perspective view of the combined crib and wardrobe looking down from the top.

I claim:

The ornamental design for a combined crib and wardrobe, substantially as shown.

EDMOND J. SPENCE.
